PIMENTO CORING MACHINE

Eston Altman, Gray, Ga.

Application June 23, 1950, Serial No. 169,872

2 Claims. (Cl. 146—52)

1

This invention relates to a machine designed for preparing pimiento peppers for canning, which necessitates removing the seed pods and stems commonly known as cores, and which have, prior to the present invention, been removed by hand, which is an exceptionally tedious and expensive operation.

An important object of the invention is to provide a machine for removing the cores of pimiento peppers, wherein the mechanism of the machine is used in conveying the pimiento peppers step by step and positioning them directly under the knives, and which forms a part of my machine for coring pears, on which the Patent No. 2,588,790, was granted to me under date of March 11, 1952.

Another object of the invention is to provide a pimiento coring machine including tubular coring knives having fingers which grip the core after the cutting operation, removing the core from the pimiento.

Still another object of the invention is to provide core knock-out members which are movable within the tubular blades of the machine and actuated by cams which are so constructed and timed that after the coring operation and the tubular blades are elevated for the following operation, the core knock-out members will move into action forcing the cores from the tubular knives freeing the knives of the cores, prior to the succeeding cutting operation to cut the cores from the pimientos.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawings

Figure 1 is a front elevational view of a pimiento pepper coring machine, constructed in accordance with the invention.

Fig. 2 is a fragmental side elevational view thereof.

Fig. 3 is a sectional view taken on line 3—3 of Fig. 1.

Fig. 4 is a sectional view taken on line 4—4 of Fig. 1.

Fig. 5 is an enlarged elevational view partly in section, illustrating the construction of one of the knives, together with the core-extracting arms and knock-out member.

2

Fig. 6 is a sectional view taken on line 6—6 of Fig. 5.

Fig. 7 is a perspective view of one of the core-removing arms.

Fig. 8 is an enlarged elevational view of a modified form of knife, portions thereof being broken away illustrating the knock-out member operating therein.

Fig. 9 is an elevational view of one of the tubular knives as shown by Fig. 8.

Fig. 10 is a vertical sectional view through a modified form of cup in which pimiento peppers are deposited for coring.

Referring to the drawings in detail, the machine comprises a stationary frame including a lower section over which chains 5 operate, the chains 5 being in parallel spaced relation with respect to each other and connected by means of the bars 6 which provide supports for the cups 7 in which the pimientos are manually positioned, the pimientos being carried step by step under the tubular cutting knives of the machine. The operating mechanism for moving the cups 7 to their proper positions under the knives, is clearly shown and illustrated in my pending application, filed July 23, 1947, Serial Number 763,003, in which the mechanism is used in carrying cups under the coring mechanism of the pear coring machine forming the subject matter of said pending application.

The frame also embodies spaced angle bars 8 arranged in spaced relation with each other at opposite sides of the frame, the angle bars being arranged in pairs to provide guideways 9 therebetween.

At the rear of the machine are vertical bars 10 which are braced by means of the bars 11 that extend from the bars 6, to the upper ends of the vertical bars 10, as clearly shown by Fig. 2 of the drawings.

The upper ends of the bars 8 and 10, are connected by means of the side bars 12 which are of lengths to extend beyond the bars 8 and 10, providing supports for an upper frame.

The pairs of bars 8 are held in spaced relation with respect to each other, by means of the transverse bars 13 which are disposed in vertical spaced relation with respect to each other, the ends of the bars 13 being disposed within the guideways 9, where they are secured against movement, by means of bolts 14.

Rising from the bars 12, and secured thereto, are rectangular frame members 15 each of which includes vertical bars 16 connected at their upper ends by the horizontal bars 17, the frame mem-

bers 15 providing supports for the bearings 18 in which the cam shaft 19 operates, the ends of the cam shaft 19 being extended beyond the bearings 18 wherein one end of the cam shaft 19 supports the sprocket 20. Collars 21 are secured to the shaft 19 and hold the shaft 19 against lateral thrust.

Mounted on the cam shaft 19 are the cams 22 that contact with the rollers 23 mounted in the bearing members 24 that are secured to the upper movable bar 25, which bar has its ends disposed within the guideways 8, maintaining the bar 25 in true horizontal position at all times.

As clearly shown by Fig. 2 of the drawings, the cams 22 which are identical in construction, are of a shape to provide an elongated structure with a gradually curved edge 26 providing a substantially pointed end 27 to the end that as the cams rotate, at one point during the cycles of rotation, the cams will operate to move the bar 25 gradually downwardly, until the pointed ends of the cams pass over the rollers 23, whereupon the bar 25 will snap upwardly, for a predetermined distance, until the rounded end of the cam contacts with the rollers 23.

Spaced an appreciable distance below the movable bar 25, is the vertically movable bar 28 which has its ends moving in the guideways 8. This bar 28 is connected with the bar 25, through the rods 29 which operate the knock-out member. While I have shown but one of these rods in Fig. 1 of the drawings, it is to be understood that there will be a coring blade and knock-out member for each line of cups 7 to the end that the bars 25 and 28 will be securely held against tilting, by the rods 29, which are secured to the bars 25 and 28, by the collars 30 that are secured to the rod 29 and frictionally engage the bars or bearings mounted thereon.

Since all of the coring blades and knock-out members used in the machine are identical, only one of these coring blades and knock-out members will be described and illustrated in this application.

The transverse bars 13, which are secured to the bars 8, provide supports for the bearings 31, through which the tubular bearing 32 operates, the tubular bearing 32 extending through the bearing 33, where it supports the pulley 34, which is secured to the tubular bearing 32. At the lower end of the tubular bearing 32, is mounted the tubular coring blade 35 to rotate therewith, the coring blade having a sharp lower edge 36 to cut the pimiento pepper, as the blade rotates and is moved thereinto.

Disposed longitudinally of the tubular coring blade 35 and extending inwardly from the cutting edge thereof, are slots 37, which slots have wide end portions 38 in which the wide ends 39 of the core gripping arms 40 operate, the lower ends of the wide ends of the core gripping arms 40 being also beveled to provide a circular cutting edge. As clearly shown by Fig. 5 of the drawings, the core gripping arms are formed with offset bearings 41 that are mounted between the ears 42 arranged in pairs, at opposite sides of the cutting blade, pivot pins 43 being provided and extended through the bearings 41 and ears 42, pivotally connecting the core gripping arms to the tubular coring blade. These core gripping arms are also provided with notches 44 that fit over the portions 45 which are formed substantially intermediate the ends of the tubular blades at points adjacent to the bearing ears 42. The upper ends of the core gripping arms are substantially wide as at 46

and are so constructed that they extend inwardly appreciable distances within the wall of the tubular cutting blade, when the gripping arms are in their normal positions as shown by Fig. 5. These wide ends have inclined inner edges 47 providing cam surfaces, for purposes to be hereinafter more fully described.

Stop pins 48 extend laterally from the core gripping arms 40 and are designed to engage the outer surface of the tubular cutting blade to restrict inward movement of the upper ends of the core gripping arms. The lower ends of the core gripping arms rest against the band 49 which encircles the lower end of the tubular cutting blade, the band 49 being welded to the tubular cutting blade.

The reference character 50 indicates a coiled spring which is positioned around the tubular cutting blade and rests in the recesses 51 formed in the outer edges of the wide ends 46, as clearly shown by Fig. 5. Thus it will be seen that due to this construction, the coiled spring 50 normally acts to urge the upper ends of the core gripping arms inwardly, but permits of outward movement of the upper ends of said core gripping arms under conditions to be hereinafter more fully described.

The rod 29 extends through the tubular bearing 32 and carries the knock-out head 52 on the lower end thereof, the upper end of the rod 29 being extended through the bar 25 where it is provided with a stop 53 against which the coiled spring 54 engages, the spring 54 acting to normally urge the rod 29 upwardly, against the movable bar 25, which as previously stated, is moved downwardly by the action of the cams 22, the cams being so timed that this downward movement takes place at predetermined intervals.

The knock-out head 52 is of a diameter so that when the rod 29 moves upwardly to a point adjacent to the upper end of the tubular cutting blade, the head 52 will engage the inclined inner edges 47 of the core gripping arms, moving the upper ends thereof outwardly with the result that the lower ends thereof move inwardly into gripping relation with the core of the pimiento pepper, which has been cut by the tubular blade, thereby holding the core so that upon reverse movement of the tubular cutting blade and rod 29, the knock-out head 52 will engage the core held between the arms and force it from its position between the arms, clearing the tubular blade for the next cutting operation.

It will of course be understood that this reverse movement of the knock-out head takes place as the cams 22 move to positions wherein the substantially pointed ends 27 thereof move over the rollers 23 forcing the bar 25 and rods 29 connected therewith, downwardly.

As clearly shown by Fig. 1 of the drawings, the tubular cutting blade is supported within the guide ring 53', the opening 54' of the guide ring having its wall beveled so that it will be guided over the upper end of the pimiento pepper being cored, to hold the pimiento pepper against tilting during the coring operation.

Extending from the opposite sides of the guide ring 53', are arms 55, which arms are provided with openings through which the rods 56 extend, the rods also extending through the tubular bearings 57 that are secured to the movable bar 58 at the bottom of the frame, the movable bar 58 having its ends disposed within the guideways 8. These rods 56 are disposed at opposite sides of the tubular cutters and move downwardly with the downward movement of the rods 29.

The reference character 59 indicates coiled springs that encircle the rods 56 bearing against the arms 55 at their lower ends, while the upper ends thereof engage the lower ends of the tubular bearings 57, the springs 59 acting to normally urge the guide ring downwardly. At the ends of the rods 56, are nuts 60 which secure the rods 56 to the arms 55 and the upper ends of the rods to the plates 61 that in turn are secured to the bar 58.

Coiled springs 62 are arranged in pairs at opposite sides of the spaced angle bars 8 and have their upper ends secured to the transverse fixed bar 13 directly below the movable bar 28, by means of the plates 63 that are secured to the bars 13 and 58 respectively. These springs have hooked ends hooked into eyes of the securing means, in such a way that the springs 62 will normally act to draw the movable bar together with the elements supported thereby upwardly.

In the form of the invention as shown by Figs. 8 and 9 of the drawings, the tubular coring blades 64 are provided with slots extending inwardly from one end thereof, in which the blades 65 are pivotally mounted, the blades 65 acting in the same capacity as the core gripping arms shown by Figs. 5 and 7 of the drawings. In this form of the tubular coring blades, the blades 65 extend below the beveled cutting ends of the tubular coring blades as shown by Figs. 8 and 9, the cutting ends 66 thereof being curved so that they contact the pimiento pepper being cored, prior to the engagement of the beveled cutting edge of the tubular coring blade, to cut the pepper prior to the entrance of the tubular cutting blade, into the pepper.

In Fig. 10 of the drawings, I have illustrated a modified form of cup, in which the upper edge of the cup is provided with an annular flange 67 which forms a support for the pimiento pepper after it has been cored and retains the pepper against falling from the cup prematurely.

The frame of the machine also includes space bars 68 that provide a support for the motor 69 which is provided with the motor shaft 70 on which the pulley 71 is secured, the pulley 71 transmitting movement to the pulley 72 through the medium of the belt 73 that moves thereover. The pulley 72 is mounted on one end of the shaft 74 on which the pulley 75 is secured, the pulley 75 rotating the pulley 76 through the medium of the belt 77 which is shown as moving over the pulleys 75 and 76. The pulley 76 is secured to the shaft 78 to which the sprocket 79 is secured, the sprocket 79 driving the substantially large sprocket 80 through the medium of the chain 81. The sprocket 80 is secured on one end of the shaft 81' and rotates said shaft 81' on which the sprocket 82 is secured. The sprocket 82 transmits rotary movement to the sprocket 83 through the medium of the chain 84 the sprocket 83 being secured to the shaft 85 to which the sprocket 86 is also connected. The sprocket 86 transmits rotary motion to the shaft 19 on which cams 22 are secured, through the medium of the sprocket 20 and chain 87 which moves over the sprockets 20 and 86, the chain also moving over the idle sprocket 88. The shaft 85 provides the support for the cams 88', to which the cams are secured, the cams 88' operating over the rollers 89 that are mounted in brackets 90 adjustably secured to the movable bar 28, so that with each complete rotation of the cams 88', the movable bar 28 will be moved downwardly against the action of the springs 62, which springs act to im-

mediately return the movable section of the machine to its uppermost position allowing another row of pimientos to be moved under the coring blades.

- 5 The coring blades which are mounted at the lower ends of the tubular bearings 32 of the machine, are rotated by means of the pulleys 34 which are secured to the upper ends of the tubular bearings 32, the pulleys 34 being rotated 10 by means of the pulleys 88'' which are secured to the shaft 74 and which transmit movement to the pulleys 34, through the belts 89'.

In the operation of the pimiento coring machine, the machine is set in operation, and the 15 pimientos are placed by hand, into the cups 7. The cups now move forwardly from the rear of the machine, towards the front end of the machine, and because of the shape of the cams 88', the coring blades 35 which are rapidly rotating, are gradually moved into contact with the pimiento to be cored. As the cams 88' and 22 20 continue to rotate, the rods 29 of the knock-out heads 52 are moved upwardly, the heads 52 contacting with the inclined inner edges 47 of the wide ends 46 of the core gripping arms 40, swinging the lower ends 39 of the core gripping arms 40 inwardly, gripping the core which has been 25 cut by the rapidly rotating tubular coring blade. The tubular coring blade is now elevated to a position above the cored pimiento pepper retained in the cup directly therebelow, and the tubular coring blade begins its downward movement for the next operation. When the knock-out head 52 moves away from the enlargements 30 35 40 45 46 of the core gripping arms, the arms return to their normal operative position as shown by Fig. 5, releasing the core which drops through the machine. It might be further stated that the shape of the cams 22 is such that an intermittent movement is transmitted to the rods 29 which results in a movement of the knock-out heads to actuate the gripping arms to grip and release the core at such time as to free the tubular coring blades of the cores cut, so that they will be in a position to continue or repeat the operation, as the pimiento peppers are fed or deposited in the cups.

As the endless chains of coring cups pass over the front end of the machine, it is obvious that 50 the cored pimiento peppers will be dropped therefrom into containers which may be placed at the delivery end of the machine.

Having thus described the invention, what is claimed is:

- 55 1. In a machine for coring pimiento peppers, a frame, an endless carrier mounted on the frame, rows of cups mounted on the endless carrier, vertically movable rotary tubular members mounted within the frame and disposed above 60 said cups, the lower edges of said tubular members being beveled providing cutting blades, said tubular members having slots extending upwardly from the cutting edges thereof, vertical blades pivotally mounted within said slots, each of said 65 blades having a lower cutting end with an edge curved about a horizontal axis disposed beyond the cutting ends of said tubular members adapted to cut a pimiento prior to the engagement of the pimiento with the cutting ends of said tubular members, means for rotating said tubular members and simultaneously advancing said tubular members into said pimientos, and means for ejecting the cores from said tubular members.

- 70 2. In a machine for coring pimiento peppers, a frame, an endless conveyor mounted on the frame,

rows of cups mounted on the endless conveyor into which peppers to be cored are placed, vertically movable rotary tubular members having their lower edges beveled providing cutting ends, said tubular members having slots extending longitudinally from the cutting edges thereof, cutting blades pivotally mounted on said tubular members and disposed within said slots, each of said cutting blades having a lower cutting end with an edge curved about a horizontal axis, disposed beyond the cutting ends of said tubular members adapted to cut a pimiento prior to the engagement of the pimiento with the cutting ends of said tubular members extending into the interior of said tubular members providing cams, knockout members slidably mounted through said tubular members, said knockout members including heads adapted to contact with said wide ends moving the cutting ends of said blades inwardly gripping

the core removed by said tubular members, means for restricting outward movement of said cutting ends of the blades, and means for biasing the opposite ends of said blades towards each other.
